MANIFOLDING

Louis C. Antrim, New York, N. Y., assignor to
 Autographic Register Company, Hoboken,
 N. J., a corporation of New Jersey

Application January 26, 1938, Serial No. 187,044

14 Claims. (Cl. 197—133)

This invention relates to the art of manifolding, and more particularly, to the making of manifold copies in a typewriting machine and maintaining the copies, which are usually printed in registration so that matter written on the top or original copy will be reproduced in the same place on the under copies.

Heretofore it was proposed to secure together in registration a plurality of record strips interleaved with a plurality of carbon strips, both in continuous form, so that the manifolding pile thus formed could be fed with the several strips traveling substantially as one.

The product thus formed is useful and has many advantages in many applications. In feeding such strips around a cylindrical platen of a typewriter by friction, however, there is an inherent differential movement or creep between the several strips of the pile and resulting from each strip on the platen adding to the effective diameter thereof. The difficulty is well known by those skilled in the art, and the phenomena is known as creeping.

The difficulty has been avoided by positively feeding the strips around the platen rather than frictionally, but this requires the provision of sprocket holes in the pile of paper and sprockets or pin-bearing bodies traveling with the platen to engage the sprocket holes.

I have found that when a pile of strips, which are secured together at intervals, as, for instance, by staples, is fed around the platen, there is a slight bunching or crinkling of the papers when the staple or other securing means is reached by the feed mechanism, and that, sometimes, this bunch is pressed down and passes the feed mechanism, but more often, after a number of forms have been fed, the creep between the several strips is sufficient to cause the paper to tear away from the staple with the result that the several record strips fail to register with each other.

According to the present invention, the very satisfactory and desirable fastened pile of manifolding strips may be used with the friction type feed, requiring no rows of marginal sprocket holes.

This is accomplished by providing, in the pile of strips, physical alterations at predetermined intervals, and arranging the feed mechanism so that pressure rollers will enter the physical alterations periodically in the feeding of the pile, and thereby relieving the pile from feeding pressure and freeing the several strips for relative movement into registration as fixed and controlled by the strip-securing means. In this rela-

tive movement, the creep inherently accumulated in the pile during the frictional feeding of that portion of the strip in advance of the physical alterations is dissipated.

5 In the form of the invention herein disclosed, the physical alterations are usually in the form of operative notches located in the side margins of the pile, and the feeding means is in the form of annuli or disks in longitudinal alignment with the feed-arresting apertures, so that when the disks enter the apertures, the strips are relieved of feeding pressure as aforesaid, and the slight bunch in advance of the securing means may become smoothed out.

10 These notches not only cause the feeding pressure on the strips to be relieved, but, also, interrupt the feeding operation, so that, in a few idle operations of the platen, the paper strips may and will be jogged into alignment with each other as controlled by the securing means, usually staples preferably secured in substantial lateral alignment with the notches. To assure the possibility of rotating the platen without advancing the strip when the feeding disks are in the apertures of the strips, there is preferably provided between the lowermost one of the pile of strips and the platen, and preferably close to the line of engagement of the pressure disks with the paper and platen, a dragbar or other device for retarding the free advancement of the paper strips.

15 According to the present invention, the usual paper table of any commercial typewriting machine is employed to cause the pile of strips to be introduced to the platen and to generally conform to the curvature of the platen as the printing point of the machine is reached, but the usual feed rollers are dispensed with or rendered inoperative, and the pressure roller of the present invention, which preferably engages the paper and the platen above the writing line, serves as the means for causing the pile of paper strips to travel with the platen.

20 The feed-arresting pressure-relieving notches in the pile of the present invention are usually spaced along the pile at form-length intervals, and are preferably located coextensive with transverse lines of weakness along which one form or sheet-length of the pile may be severed from the remaining.

25 It will be seen that the present invention does not contemplate the elimination of creep during the feeding of each form-length, but, rather, dissipates the creep at each form-length and avoids the accumulation of creep from form-length to form-length which would cause the several strips

to shift out of registration with each other. The amount of creep existing for any one form-length is not sufficient to be commercially unacceptable, but any creep extending for several form-lengths would be unacceptable for practical purposes.

The pile of papers which has come to rest for realignment to dissipate the creep may be restarted in any suitable manner. The operator may place her finger against the pile while line-spacing the platen to thereby cause the pile to travel with the platen until the feeding disks have passed out of the feed-arresting pressure-relieving apertures. Preferably, however, some mechanical means is employed for this purpose, and in one form of this invention shown herein, a separate starting roller is employed for frictionally pressing a portion of the paper remote from the apertures against the platen during the starting movement. This starting means is preferably located somewhere between the securing means and one or both of the lateral margins of the pile.

In the broader aspects of the invention, the feed-arresting apertures may be contained within the body of the strips, or they may be at the top of a form or near the bottom, and even when contained in the body of the form, they may be coincident with the line of weakness between forms.

It is preferable, however, to have the notches in the side margins, for then the pressure rollers will engage the extreme side margins of the pile, and these margins on the carbon strips may be either removed or left uncarbonized, thereby avoiding the production of marks on the under copies produced by the overlying carbon strips being pressed thereagainst by the rollers.

Attention is called to a companion application filed concurrently herewith in which the manifolding piles described and illustrated herein are described and claimed per se, for, while the manifolding piles illustrated herein cooperate in a special way with the typewriter and parts thereof, these manifolding piles are capable of use with mechanism quite different from the mechanism herein disclosed.

Other features and advantages will hereinafter appear, and in the accompanying drawings:

Fig. 17 is a top plan view of a typewriting platen showing the present invention applied thereto and showing the starting mechanism shown in Figs. 15 and 16.

Fig. 18 is a front view of the device shown in Fig. 17.

As shown in the accompanying drawings, the invention is applied to a front-strike typewriting machine having a cylindrical platen 10 mounted in a carriage frame 11, which, usually, is provided with feed rollers 12 adapted to press worksheets or strips against the platen to cause the same to advance therewith as the platen is rotated line-by-line by line-spacing mechanism including a ratchet wheel 13 mounted on a shaft 14 carrying the platen and itself rotatably mounted in the carriage frame 11.

Paper sheets or strips are guided to the platen by a paper table 15, and an apron 16 causes the paper to follow the curvature of the platen and lie close thereto at the line of writing 17 where typebars 18 strike upon the platen.

The feed rollers 12 may be released by the operation of a lever 19 and linkage 20 so as to be spaced from the platen and to likewise drop the paper apron for the usual introduction of the paper to the platen.

The machine has a bail, including side arms 21, which usually supports between them a rod which carries a pair of auxiliary pressure rollers engaging the work in advance of the line of writing. The arms 21 are usually yieldingly mounted, but, in adapting the machine to the present invention, the arms 21 are locked down by latches 22 pivoted at 23 on the carriage. The rod and auxiliary rollers supplied with the machine are also discarded.

As stated above, the present invention provides for continuously making manifolding records without resorting to the use of feeding pins or the like, or the provision of pin-engaging apertures in the record strips and yet maintain satisfactory registration between the printed matter on the several record strips.

This is accomplished by such organization of and cooperation between the manifolding pile, including the record and transfer strips and the feeding parts of the typewriter that, while the pile is fed frictionally line-by-line past the line of writing, the feeding pressure on the pile of strips is released periodically to allow the creep accumulated between the several strips to be dissipated by the natural tendency of the strips

75 to realign under the control of means securing

all of the strips together in registration. The strips are assisted in becoming realigned by the jogging of the machine incident to the travel of the carriage and the idle rotation of the platen while the pile of strips is relieved of feeding pressure.

As illustrated in the accompanying drawings, the manifolding pile is made up of a plurality of record strips 24, each continuous, and provided with a succession of printed forms 25. Interleaved with the record strips 24 are a plurality of continuous carbon sheets 26. The record strips 24, and preferably the carbon strips 26 also, may be provided with transverse lines of weakness 27, usually lines of perforations, dividing the strips and the pile as a whole into form or sheet-lengths adapted to be separated from the remainder as form after form is written.

The pile of strips 24 and 26 is held together in registration so that the typewriting performed on the uppermost strips is reproduced on the other strips in substantially the same places, by staples 28 in the form illustrated, but other forms of securing means known to the art or found suitable may be employed. The staples 28 are preferably located directly on the lines of weakness 27 in the record strips so that when a completed set of forms is torn off, the staple is no longer operative to hold the resulting record sheets together, and the resulting carbon sheets may be separated therefrom. To facilitate this, the lines of separation in the carbon strips may deviate, in the now well known manner, from those of the record strips so that tabs 29 are formed on the carbon sheets at one end of the pile of sheets and notches 30 are formed in the carbon sheets at the other end of the pile. By grasping the tabs 29 of the carbon sheets with the fingers of one hand and the record sheets over the notches 30 at the other end of the pile and drawing the hands apart, the carbon sheets and the record sheets are stripped from each other. By placing the staple 28 in the portion of the sheets adjacent the tabs 29, the entire group of carbon sheets is held together as a unit in the stripping operation, and the staple is prevented from falling into the typewriting machine where it might cause trouble. With the strips 24 and 26 stapled or otherwise fastened together at intervals along the pile, as the pile is fed frictionally the inherent tendency to creep causes the strips to advance at different rates of speed, depending upon their nearness to the platen.

The excess of paper incidental to each form fed must be bunched in advance of the staple and pass by the feeding means, otherwise it accumulates from form to form until the excess becomes so great that the paper tears loose from the staple and practical registration is destroyed. Reliance cannot be placed upon the bunch of excess paper going through the feed mechanism without tearing away from the staple, and hence it is customary for operators using stapled paper to remove the paper from the machine from time to time and cause it to register.

To obviate the necessity of doing this and to positively avoid creep accumulating from form to form, the manifolding pile of the present invention is provided with physical alterations, preferably apertures, and the feeding means comprises relatively narrow disks or annuli adapted to enter the apertures or other physical alterations and relieve the pile of strips of feeding

pressure so that the creep accumulated during the feeding of one form-length in advance of the staple may be dissipated.

In the form of the invention shown in Figs. 1 to 6, the physical alterations are in the form of notches 31 provided in pairs along the lateral margins of the pile. When the carbon strips 26 are full width as shown in Fig. 5, they, too, are provided with notches 31, but, when the carbon strips are narrow as shown in Fig. 6, they need not be provided with the notches. If the carbon strips 26 are wider than shown in Fig. 6 but not as wide as shown in Fig. 5, they will be notched as much as needed to conform with the notches in the edges of the record strips 24.

In practicing the present invention, the usual feed rollers 12 are released by the operation of the lever 19 so that the pile of strips is substantially free of feeding engagement with the platen below the line of writing 11.

The pile of strips is advanced, according to the present invention, by a pair of feeding disks 32, one at each side of the machine, and located in longitudinal alignment with the notches 31. The feeding disks 32 are carried by a rod 33 mounted in arms 34 pivoted at 35 on the arms 21 of the usual auxiliary roller bail. The arms 34 extend rearwardly and are provided with springs 36 connected to a bar 37 on the machine, so that the rollers 32 are yieldingly pressed against the platen and the pile of papers carried thereby. To keep the bail arms 21 from being raised as a result of the pressure of the rollers 32 against the platen, they are provided with a pin 38 engaging a notch in the locking arms 22 referred to above.

After the leading edge of the manifolding pile is placed on the paper table 15 and is introduced around the platen and placed under the pressure disks 32, the rotary movement of the platen will cause the pile of strips to advance line-by-line with the platen until the notches 31 reach the bight of the rollers 32, at which time the rollers enter the notches and relieve the pile of strips 24 from feeding pressure. When the strips 24 and 26 are thus relieved, they may shift relatively to dissipate any creep or relative movement which has occurred between the strips during the feeding of one-form length and assumed proper registration as controlled by the securing means, such as the staple 28.

Preferably, the feed-arresting notches 31 are in lateral alignment with the staples so that the strips are relieved from feeding pressure just about the time when the maximum amount of creep exists, thereby avoiding carrying over to the next form any of the creep, even though that amount of creep is not sufficient to cause the staple to tear through the paper.

Preferably, also, the notches 31 are coincident with the lines of weakness 27 which preferably carry the staples 28, for the notches facilitate the starting of the tearing operation when the written form is to be torn off along the lines of weakness, and, when the staple is located on the line of weakness, it will be removed with the carbons of the written form being located in the tab 29.

The resiliency of the paper is sufficient in most cases to cause the bunch in advance of the staple to disappear immediately upon the release of the feeding pressure. However, the idle operation of the machine, that is to say, the rotation of the platen, and the return of the carriage while the feeding pressure is relieved, also tends to

jog the several strips into registration. Besides this, the engagement of the feeding disks with the leading edges of the apertures, that is to say, the bottom edge of the written form in the construction shown in Figs. 1 to 6, also tends to move the strips into registration and particularly into alignment with the line of writing of the typewriting machine.

To insure against the platen inadvertently advancing the pile of strips while the disks 32 are located in the notches 31 or other apertures performing the same function, the present invention provides a drag plate 39 adapted to be located between the platen and the pile of strips and between the writing line 17 and the bight of the disks 32. The plate 39 sufficiently separates the pile of strips from the platen so that rotation of the platen while the disks are in the apertures does not advance the strips. The form and position of the drag plate shown in the accompanying drawings has been found satisfactory in use, but it should be understood that any suitable separating and retarding device may be employed.

In the form of the invention herein disclosed, the plate 39 has vertical ears 40 secured to arms 41 carried on the pins 38 in the bail arms 21.

The separating and retarding plate 39 may be provided with lateral guides 42, which, in co-operation with lateral guides 42a on the paper table 15, assist in keeping the pile in proper position on the platen with the notches 31 longitudinally aligned with the feeding disks 32.

So long as the feeding pressure of the disks 32 is not applied to the pile of strips, the platen may be operated idly without advancing the strips. To cause the strips to again advance, the pressure may be applied to the strips so that they frictionally engage the platen in any suitable way. This may be accomplished by temporarily returning the feed rollers 12 to operative position, or it may be accomplished by the operator pressing her finger against the pile of papers on the platen while line-spacing the same.

However, it is preferable to have a mechanical device to perform this function, and, as shown in Figs. 2, 3 and 4, the present invention provides auxiliary pressure rollers 43 carried by a frame 44 urged to inoperative position by a spring 45 and provided with a finger-piece 46 whereby the rollers 43 may be swung down into engagement with the pile of papers on the platen at a point remote from the apertured portions of the strips. With the frame 44 held down as shown in Fig. 3, line-spacing movement of the platen causes the paper strips to advance until the pressure disks 32 move out of the notches 31 and again engage the lateral margins of the paper strips.

The starting rollers 43 are so placed on the frame as to produce a downward pressure on the paper without themselves tending to advance the paper, for, if this occurred, the top strip, which is directly engaged by the starting rollers, might be shifted out of registration.

When the starting mechanism is located midway between the pressure rollers 32, that is, at the center of the paper strips, it might be interfered with by the staple 28, and hence, in the form shown, there are two starting rollers 43 connected together by a sleeve 47 separated a sufficient distance to straddle the staple.

In Figs. 15, 16, 17 and 18, a different form of starting mechanism is shown. In this form of the invention, the starting roller 48, preferably of rubber or other soft material, is ro-

tatably mounted on the rod 33 which supports the pressure rollers and has diametrically opposite cutaway portions 49, one of which normally faces the paper strips and the platen. The roller 50 has a sleeve portion 50 having two flats parallel with the cutaway portions 49, and these are engaged by a leaf spring 53 mounted on a collar 54 carried by the rod 33 so that a cutaway portion 49 is normally located in the position shown in Fig. 15. The spring 53 may be covered and protected by a housing 55. The starting roller 48 also has a pair of pins 56. These are so located as to be engaged by a lug 57 on a key 58 pivotally mounted at 59 on a bracket 60 secured to the rod 33 and having a spring 61 adapted to hold the key in the position shown in Fig. 15. When it is desired to start the strips so that they will advance with the platen, the key 58 is depressed causing the lug 57 to engage one of the pins 56 and rotate the starting roller until the periphery thereof just engages the paper as shown in Fig. 16. With the parts in this position, the platen is line-spaced, and this causes the pile of strips to be pressed against the platen by a starting roller 48. When this has occurred, the key 58 is released, removing the lug 57 to the position shown in Fig. 15 so that the other pin 56 may be moved to the position shown in Fig. 15 as the starting is rotated one half revolution, which movement is completed by the spring 53 which holds the starting roller in this position until the starting operation is to be manually initiated and repeated.

The rod 33 is held in the arms 34 against turning, and, therefore, the parts of the starting mechanism which are not intended to rotate may be secured in fixed position on the rod 33.

The feeding disks 32 are adjustable longitudinally of the rod 33 so as to bring them into proper alignment with the feed-arresting apertures in the paper strips. They may conveniently be held in adjusted position by collars 62.

When the feeding disks engage the lateral margins of the record strips 24, any tendency for the feeding disks to cause marks to be made on the under copies through the carbon may be avoided by providing on the full-width carbon strip 26 a clean marginal band 63, as shown in Fig. 5, but, if this is not desirable, the carbon strip may be made narrow so as not to extend to the line of feed in the record strips, as shown in Fig. 6.

In the broader aspects of this invention, the feed-arresting form-registering apertures in the strips need not be in the lateral margins, but, as shown in Figs. 7 to 13, inclusive, they may be located inwardly of the margins of the strips.

In the form of the invention illustrated in Fig. 7, there are employed circular apertures or holes 64 located a substantial distance from the lateral margins of the pile. In Fig. 9, the apertures 64 are located in the head of the form so that the staple is in advance of the apertures. This construction may be used advantageously where the bunching which results from the feeding of one form-length is not sufficient to tear the staple from the paper, for the creep will be dissipated when the feeding disks enter the apertures 64, even though the staple has passed the line of feed before the feeding pressure is relieved.

In Fig. 11, there are apertures 65, like the apertures 64, but placed in the foot of the form. Here the creep is dissipated before the staple reaches the line of feed, and, for this reason, the form shown in Fig. 11 may under some con-

ditions be preferable to the form shown in Fig. 9.

The feed-arresting apertures need not be round holes as in Figs. 7, 9 and 11, but may be of any desired shape. For instance, they may be oblong as shown in Figs. 8, 10, 12 and 13, or square, so that the feeding disks or annuli 32 may enter the apertures and relieve the paper strips of feeding pressure.

Again, the marginal apertures need not be in the form of notches, as in Figs. 1 to 6, but may be located in the margins of the strips and be in the form of holes, such as the holes 66 in Figs. 8, 10, 12 and 13, which do not intersect the lateral edges of the paper strips.

With the constructions shown in Figs. 8, 10, 12 and 13, it is possible to have the feeding disks engage the paper without danger of marking the under copies, and yet the lateral edges of the paper strips are continuous and may be more easily guided by usual lateral guides in manufacturing the manifolding pile and in using it in the typewriter.

When the apertures are in the foot of the form with parts coincident with the weakened tear lines 27, as in Fig. 13, the feeding pressure on the strips is relieved just at the time that the staple reaches the line of feed.

The feed-arresting holes 64 and 66 may be off the lines of weakness 27, as in Figs. 7 to 11 inclusive, or may be partially thereon like the notches 31 in Figs. 5 and 6, and they may be behind the lines of weakness 27 as in Fig. 12 or in advance as in Fig. 13.

Likewise, the notches in the lateral margins need not be in the lines of weakness as in Figs. 1 to 6. Instead as shown in Fig. 14, the notches 31 may be removed more or less from the tear lines 27.

Regardless of the locations of the apertures, the feeding disks 32 are, as shown in Fig. 8, brought into longitudinal alignment with the apertures so that the feeding pressure is relieved when the apertures reach the line of feed.

Variations and modifications may be made within the scope of this invention and portions of the improvements may be used without others.

I claim:

1. A typewriter comprising a rotatable platen adapted to support a manifolding pile having a plurality of superposed and interleaved record and transfer strips divisible into sheet-lengths, said strips having in their lateral margins feed-arresting apertures at sheet-length intervals, and said strips having means located at sheet-length intervals for securing the strips of the pile together in registration; means for advancing the platen line-by-line; yielding feeding means for pressing the manifolding pile against the platen to advance therewith, said feeding means being located in longitudinal alignment with said feed-arresting apertures so as to enter said apertures after a sheet-length of said manifolding pile has been fed to relieve the pile from feeding pressure and free the several strips for relative movement into registration fixed and controlled by said strip securing means upon relief of feeding pressure to thereby dissipate the creep inherently accumulated in the pile during the frictional feeding of one sheet-length with and around the rotatable platen; and means adjacent the platen and over which the strips pass to relieve the strips from binding engagement with the platen to prevent the pile from being advanced inadvertently by the platen

while the feeding means are located in said feed-arresting apertures.

2. A typewriter comprising a rotatable platen adapted to support a manifolding pile having a plurality of superposed and interleaved record and transfer strips and securing means for securing the strips together at predetermined intervals, said strips having feed-arresting apertures therein located between each of said securing means; means for advancing the platen; a pair of spaced feeding disks and yielding mounting means therefor for pressing the manifolding pile against the platen to advance therewith, said disks being located in longitudinal alignment with said feed-arresting apertures and adapted to enter said apertures after a predetermined length of said manifolding pile has been fed to relieve the pile from feeding pressure and free the several strips for relative movement into registration fixed and controlled by said securing means and thereby dissipate the creep inherently accumulated in the pile in advance of the securing means during the frictional feeding of said predetermined length with and around the rotatable platen; and means interposed between the strips and the platen and located adjacent the line of engagement of the feeding disks with the platen to relieve the pressure of the strips against the platen for preventing the strips from being inadvertently advanced by the platen while the feeding disks are located in said feed-arresting apertures.

3. A typewriter comprising a rotatable platen adapted to support a manifolding pile having a plurality of superposed and interleaved record and transfer strips and securing means for securing the strips together at predetermined intervals, said strips having feed-arresting apertures therein located between each of said securing means; means for advancing the platen; a pair of spaced feeding disks and yielding mounting means therefor for pressing the manifolding pile against the platen to advance therewith, said disks being located in longitudinal alignment with said feed-arresting apertures and adapted to enter said apertures after a predetermined length of said manifolding pile has been fed to relieve the pile from feeding pressure and free the several strips for relative movement into registration fixed and controlled by said securing means and thereby dissipate the creep inherently accumulated in the pile in advance of the securing means during the frictional feeding of said predetermined length with and around the rotatable platen; and a separator member adjacent the platen and interposed between the strips and the platen to relieve the pressure of the strips against the platen for preventing the strips from being advanced by rotation of the platen while the feeding disks are in said feed-arresting apertures.

4. A typewriter comprising a rotatable platen adapted to support a manifolding pile having a plurality of superposed and interleaved record and transfer strips divisible into sheet-lengths, said strips having feed-arresting apertures at sheet-length intervals, and said strips having means located at sheet-length intervals for securing the strips of the pile together in registration; means for advancing the platen line-by-line; yielding feeding means for pressing the manifolding pile against the platen to advance therewith, said feeding means being located in longitudinal alignment with said feed-arresting apertures and being adapted to enter said apertures

after a sheet-length of said manifolding pile has been fed to relieve the pile from feeding pressure and free the several strips for relative movement into registration fixed and controlled by said strip securing means and thereby dissipate the creep inherently accumulated in the pile during the frictional feeding of one sheet-length with and around the rotatable platen; means disposed between the platen and the strips for spacing the lowermost strip in the pile from the platen to prevent feed of the pile by the platen while the feeding means is located in said apertures; and manually operable means engaging a portion of the pile offset from said feeding means for pressing the pile against the platen to cause the pile to advance therewith until the feeding means pass out of said notches and onto the pile.

5. A typewriter comprising a rotatable platen adapted to support a manifolding pile having a plurality of superposed and interleaved record and transfer strips divisible into sheet-lengths, said strips having feed-arresting apertures at sheet-length intervals, and said strips having means located at sheet-length intervals for securing the strips of the pile together in registration; means for advancing the platen line-by-line; yielding feeding means for pressing the manifolding pile against the platen to advance therewith, said feeding means being located in longitudinal alignment with said feed-arresting apertures and being adapted to enter said apertures after a sheet-length of said manifolding pile has been fed to relieve the pile from feeding pressure and free the several strips for relative movement into registration fixed and controlled by said strip securing means and thereby dissipate the creep inherently accumulated in the pile during the frictional feeding of one sheet-length with and around the rotatable platen; drag-releasing means for preventing the manifolding pile from being advanced inadvertently by the drag of the platen upon rotation of the same while said feeding means is located in said feed-arresting apertures; and manually operable means engaging a portion of the pile for pressing the pile against the platen in advance of said drag-releasing means to cause the pile to advance with the platen as the same is advanced line-by-line until the feeding means pass out of said notches and onto the pile.

6. A typewriter comprising a rotatable platen adapted to support a manifolding pile having a plurality of superposed and interleaved record and transfer strips divisible into sheet-lengths, said strips having feed-arresting apertures at sheet-length intervals, and said strips having means located at sheet-length intervals for securing the strips of the pile together in registration; means for advancing the platen line-by-line; yielding feeding means for pressing the manifolding pile against the platen to advance therewith, said feeding means being located in longitudinal alignment with said feed-arresting apertures and being adapted to enter said apertures after a sheet-length of said manifolding pile has been fed to relieve the pile from feeding pressure and free the several strips for relative movement into registration fixed and controlled by said strip securing means and thereby dissipate the creep inherently accumulated in the pile during the frictional feeding of one sheet-length with and around the rotatable platen; and means between the platen and the manifolding pile and located adjacent the line of engagement of the feeding disks with the platen for spacing the pile from the platen and breaking the contact therebetween to prevent the manifolding pile from being advanced inadvertently by the platen while the pressure disks are located in said feed-arresting, form-registering notches; and means engaging the pile between the securing means thereof and at least one of said feeding disks for pressing the pile against the platen to cause the pile to advance therewith until the pressure disks pass out of said notches and onto the pile.

of the line of engagement of the feeding means with the platen for separating the platen from the lowermost strip of the pile to prevent the same from being advanced inadvertently by the platen while the feeding means are located in said feed-arresting apertures.

7. A typewriter comprising a rotatable platen adapted to support a manifolding pile having a plurality of superposed and interleaved record and transfer strips divisible into sheet-lengths, said strips having feed-arresting apertures at sheet-length intervals, and said strips having means located at sheet-length intervals for securing the strips of the pile together in registration; means for advancing the platen line-by-line; a pair of feeding disks and yielding mounting means therefor for pressing the manifolding pile against the platen to advance therewith, said disks being located in longitudinal alignment with said feed-arresting form-registering apertures and being adapted to enter said apertures after a sheet-length of said manifolding pile has been fed to relieve the pile from feeding pressure and free the portion of the several strips in advance of the securing means for relative movement into registration fixed and controlled by said securing means and thereby dissipate the creep inherently accumulated in the pile in advance of the securing means during the frictional feeding of one sheet-length with and around the rotatable platen; and manually operable means swingable into engagement with the pile between the securing means thereof and at least one of said feeding disks for pressing the pile against the platen to cause the pile to advance therewith until the pressure disks pass out of said notches and onto the pile.

8. A typewriter comprising a rotatable platen adapted to support a manifolding pile having a plurality of superposed and interleaved record and transfer strips divided by lines of weakness into sheet-lengths, said strips having in their lateral margins feed-arresting notches coextensive with said lines of weakness, and said strips having means located on said lines of weakness for securing the strips of the pile together in registration; means for advancing the platen line-by-line; a pair of feeding disks and yielding mounting means therefor for pressing the manifolding pile against the platen to advance therewith, said disks being located in longitudinal alignment with said feed-arresting form-registering notches and being adapted to enter said notches after a sheet-length of said manifolding pile has been fed to relieve the pile from feeding pressure and free the several strips for relative movement into registration fixed and controlled by said securing means and thereby dissipate the creep inherently accumulated in the pile in advance of the securing means during the frictional feeding of one sheet-length with and around the rotatable platen; means between the platen and the manifolding pile and located adjacent the line of engagement of the feeding disks with the platen for spacing the pile from the platen and breaking the contact therebetween to prevent the manifolding pile from being advanced inadvertently by the platen while the pressure disks are located in said feed-arresting, form-registering notches; and means engaging the pile between the securing means thereof and at least one of said feeding disks for pressing the pile against the platen to cause the pile to advance therewith until the pressure disks pass out of said notches and onto the pile.

9. A typewriter comprising a rotatable platen adapted to support in the line of writing of the platen a manifolding pile having a plurality of superposed and interleaved record and transfer strips divisible into sheet-lengths, said strips having feed-arresting apertures at sheet-length intervals, and said strips having means at sheet-length intervals for securing the strips of the pile together in registration; means for advancing the platen line-by-line; a pair of feeding disks and yielding mounting means therefor for pressing the manifolding pile against the platen at a point in advance of the line of writing to advance therewith, the pile extending around the platen from the introductory side thereof to the feeding disks and conforming substantially to the curvature of the platen; and means for rendering the manifolding pile normally free of feeding engagement with said platen other than by said disks, said disks being located in longitudinal alignment with said feed-arresting apertures and being adapted to enter said apertures after a sheet-length of said manifolding pile has been fed, to relieve the pile from feeding pressure and free the portions of the several strips in advance of the securing means for relative movement into registration fixed and controlled by said strip securing means and thereby dissipate the creep inherently accumulated in the pile in advance of the strip securing means during the frictional feeding of one sheet-length with and around the rotatable platen.

10. A typewriter comprising a rotatable platen adapted to support in the line of writing of the platen a manifolding pile having a plurality of superposed and interleaved record and transfer strips divisible into sheet-lengths, said strips having feed-arresting apertures at sheet-length intervals, and said strips having means at sheet-length intervals for securing the strips of the pile together in registration; means for advancing the platen line-by-line; a pair of feeding disks and yielding mounting means therefor for pressing the manifolding pile against the platen at a point in advance of the line of writing to advance therewith, the pile conforming substantially to the curvature of the platen and extending there-around from the introductory side thereof to said pressure disks, the manifolding pile being normally free of feeding engagement with said platen other than by said disks, said disks being located in longitudinal alignment with said feed-arresting apertures and being adapted to enter said apertures after a sheet-length of said manifolding pile has been fed, to relieve the pile from feeding pressure and free the several strips for relative movement into registration fixed and controlled by said strip securing means and thereby dissipate the creep inherently accumulated in the pile in advance of the strip securing means during the frictional feeding of one sheet-length with and around the rotatable platen; and means between the platen and the manifolding pile and disposed intermediate the line of writing and the line of engagement of the pressure disks with the platen for relieving the drag and preventing the manifolding pile from being advanced inadvertently by the platen while the pressure disks are located in said feed-arresting apertures.

11. A typewriter comprising a rotatable platen adapted to support in the line of writing of the platen a manifolding pile having a plurality of superposed and interleaved record and transfer strips divisible into sheet-lengths, said strips hav-

ing feed-arresting apertures at sheet-length intervals, and said strips having means located at sheet-length intervals for securing the strips of the pile together in registration; means for advancing the platen line-by-line; a spring pressed bail; disks mounted on said bail and pressing the manifolding pile against the platen at a point in advance of the line of writing to advance therewith, the pile extending around the platen from the introductory side thereof to the feeding disks and conforming substantially to the curvature of the platen; means for rendering the manifolding pile normally free of feeding engagement with said platen other than by said disks, said disks being located in longitudinal alignment with said feed-arresting apertures and being adapted to enter said apertures after a sheet-length of said manifolding pile has been fed to relieve the pile from feeding pressure and free the portions of the several strips in advance of the securing means for relative movement into registration fixed and controlled by said strip securing means and thereby dissipate the creep inherently accumulated in the pile in advance of the strip securing means during the frictional feeding of one sheet-length with and around the rotatable platen; and a starter roller carried by said bail and manually operable to engage the pile between the portion having the strip securing means and at least one of said feeding disks for pressing the pile against the platen to cause the pile to advance therewith until the pressure disks pass out of said apertures and onto the pile.

12. A typewriter comprising a rotatable platen adapted to support in the line of writing of the platen a manifolding pile having a plurality of superposed and interleaved record and transfer strips divisible into sheet-lengths, said strips having feed-arresting apertures at sheet-length intervals, and said strips having means located at sheet-length intervals for securing the strips of the pile together in registration; means for advancing the platen line-by-line; a spring pressed bail; disks mounted on said bail and pressing the manifolding pile against the platen at a point in advance of the line of writing to advance therewith; means for guiding the pile to cause the same to conform substantially to the curvature of the platen from the introductory side thereof to said pressure disks, the manifolding pile being normally free of feeding engagement with said platen other than by said disks, said disks being located in longitudinal alignment with said feed-arresting apertures and being adapted to enter said apertures after a sheet-length of said manifolding pile has been fed to relieve the pile from feeding pressure and free the several strips for relative movement into registration fixed and controlled by said strip securing means and thereby dissipate the creep inherently accumulated in the pile in advance of the strip securing means during the frictional feeding of one sheet-length with and around the rotatable platen; and a bar between the platen and the manifolding pile and located adjacent the line of engagement of the pressure disks with the platen for relieving the pressure of the pile on the platen and preventing the manifolding pile from being inadvertently advanced by the platen while the pressure disks are located in said feed-arresting apertures, said bar having lateral guides to engage the margins of the pile of strips to maintain the same in such position on the platen that the apertures are in longitudinal alignment with the pressure disks.

13. A typewriter comprising a rotatable platen adapted to support a manifolding pile having a plurality of superposed and interleaved record and transfer strips divisible into sheet-lengths, said strips having feed-arresting apertures at sheet-length intervals, and said strips having staples located at sheet-length intervals for securing the strips of the pile together in registration; means for advancing the platen line-by-line; annular feeding means and yielding mounting means therefor for pressing the manifolding pile against the platen to advance therewith, said annular feeding means being located in longitudinal alignment with said feed-arresting apertures and being adapted to enter said apertures after a sheet-length of said manifolding pile has been fed to relieve the pile from feeding pressure and free the several strips for relative movement into registration fixed and controlled by said staple and thereby dissipate the creep inherently accumulated in the pile during the frictional feeding of one sheet-length with and around the rotatable platen; and a bar disposed between said platen and said pile for spacing and holding the pile from the platen so that said pile will not be advanced upon rotation of the platen while the annular feeding means are within the feed-arresting apertures, said bar being coextensive with said platen and being spaced as to engage the pile to the rear of the point of engagement between the annular feeding means and the pile.

14. A typewriter comprising a rotatable platen adapted to support a manifolding pile having a plurality of superposed and interleaved record

and transfer strips divisible into sheet-lengths, said strips having feed-arresting apertures at sheet-length intervals, and said strips having means located at sheet-length intervals for securing the strips of the pile together in registration; means for advancing the platen line-by-line; yielding feeding means for pressing the manifolding pile against the platen to advance therewith, said feeding means being located in longitudinal alignment with said feed-arresting apertures and being adapted to enter said apertures after a sheet-length of said manifolding pile has been fed to relieve the pile from feeding pressure and free the several strips for relative movement into registration fixed and controlled by said strip securing means and thereby dissipate the creep inherently accumulated in the pile during the frictional feeding of one sheet-length with and around the rotatable platen; means interposed between the strips and the platen so as to engage the pile to the rear of said feeding means for separating the strips from the platen and for breaking the frictional contact between the lowermost strip in the pile and said platen so that said pile will not be advanced upon rotation of the platen while the feeding means are within said apertures; and means normally spaced from said pile but manually movable into engagement therewith intermediate said feeding means and said last-named means for pressing the pile against the platen to cause the pile to advance therewith until the feeding means pass out of said notches and again engage the pile.

LOUIS C. ANTRIM.

CERTIFICATE OF CORRECTION.

Patent No. 2,247,765.

July 1, 1941.

LOUIS C. ANTRIM.

It is hereby certified that error appears in the printed specification of the above numbered patent requiring correction as follows: Page 2, second column, line 18, for "tyepwriting" read --typewriting--; line 30, for "havnig" read --having--; page 3, first column, line 46, for "togeher" read --together--; line 67, for the word "register" read --reregister--; page 7, first column, line 63, claim 10, for "manfolding" read --manifolding--; and that the said Letters Patent should be read with this correction therein that the same may conform to the record of the case in the Patent Office.

Signed and sealed this 9th day of September, A. D. 1941.

(Seal)

Henry Van Arsdale,
Acting Commissioner of Patents.
